UNITED STATES PATENT OFFICE

172,498

SLIPPER OR SIMILAR ARTICLE

Virginia J. Gilmore, San Rafael, Calif.

Application April 6, 1953, Serial No. 24,381

Term of patent 14 years

(Cl. D7—7)

To all whom it may concern:

Be it known that I, Virginia J. Gilmore, a citizen of the United States, residing at San Rafael, California, have invented a new, original, and ornamental Design for a Slipper or Similar Article, of which the following is a specification, reference being had to the accompanying drawing, forming a part hereof.

Figure 1 is a perspective view of my slipper or similar article, showing my new design,

Figure 2 is an end elevation of my slipper or similar article, and

I claim:

The ornamental design for a slipper or similar article, substantially as shown.
